C. J. KLEIN,
ATTACHMENT PLUG,
APPLICATION FILED AUG. 5, 1915.

Patented Aug. 12, 1919.

Fig. 1.

UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ATTACHMENT-PLUG.

1,312,551.

Specification of Letters Patent. Patented Aug. 12, 1919.

Application filed August 5, 1915. Serial No. 43,749.

To all whom it may concern:

Be it known that I, CHARLES J. KLEIN, a citizen of the United States, residing at Milwaukee, in the county of Milwaukee and 5 State of Wisconsin, have invented new and useful Improvements in Attachment-Plugs, of which the following is a full, clear, concise, and exact description, reference being had to the accompanying drawing, forming 10 a part of this specification.

This invention relates to separable attachment plugs.

One of the objects of the invention is to provide an improved separable plug wherein 15 the engaging contacts permit a swivel movement of the parts and also permit separation of said parts either by leverage or a straight pull.

Another object is to provide a swivel type 20 plug wherein the contacts of the base are inaccessible except through narrow slots.

Another object is to provide a plug of the aforesaid character wherein the cap thereof is provided with a central knot recess and 25 with its contacts so disposed as to render said recess unobstructed and readily accessible.

Various other objects and advantages of 30 the invention will hereinafter appear.

The accompanying drawing illustrates one 35 embodiment of the invention and the same will now be described it being understood that the invention is susceptible of other embodiments falling within the scope of the appended claims.

In the drawing,

Figure 1 is a longitudinal sectional view through the plug;

Fig. 2 is a top plan view of the base or 40 plug member;

Fig. 3 is a longitudinal sectional view through the cap taken at right angles to Fig. 1; and,

Fig. 4 is a bottom plan view of the cap.

Referring more specifically to the drawing, the same shows a base 1 having a screw shell 2 and center terminal 3 for insertion 45 in a standard lamp socket and a detachable cap 4 having a swivel connection with the base 1.

The base 1, which is of suitable insulating material, is cylindrical in form and is provided with a lower end disk 5 to clamp an inturned rim 6 of the threaded shell 2 to 50 said base. The opposite end of the base is

centrally recessed to receive an annular contact 7, shown as cup-shaped, which in turn receives a cylindrical insulating block 8. All of the aforesaid parts are secured in assembled relation by the center contact 60 screw. The contact 7 constitutes a center contact while the upper extremity of the screw shell 2 provides an outer annular contact 9 concentric with the former contact. The contact portion 9 of the screw shell is 65 surrounded by an insulating collar 10 which in practice may be molded thereon or otherwise fixed thereto to serve as a gripping member for inserting the plug in a lamp socket and also for external insulation of 70 the contact portion 9. Both contacts 7 and 9, as shown, are curved to provide concave gripping surfaces and both are closely walled in by the several insulating parts. Moreover, the insulating parts are extended 75 slightly beyond the extremities of the contacts and the extremities of the contacts are set into their surrounding insulating walls whereby only their inner faces are accessible and then only after entrance between the 80 extended insulating parts. Thus the cap receiving end of the plug part appears as a block of insulation with restricted concentric slots and presents a very neat appearance 85 while it very effectually insures against accidental engagement with the contacts.

The cap 4 is provided with the usual central conductor opening 11 and with a knot receiving recess 12 adjacent thereto. Also, the cap is provided with the usual annular rim 13 and adjacent to said rim and at diametrically opposite points with terminal plates 15 and 16 having binding screws 17. The terminal plates, as best illustrated in Fig. 3, are arc shaped and arranged concentrically with the conductor opening while being spaced from one another. Terminal plate 15 is provided with perpendicularly and oppositely disposed contact lugs 18 and 19 and terminal plate 16 is provided with 90 similar contact lugs 20 and 21, each of said lugs being arc shaped in cross section and longitudinally split to form a plurality of resilient fingers. The contact lugs are 95 concentrically arranged with respect to the axis of the plug thereby giving free access to the knot recess and are so disposed as to register with the annular slots in the base for insertion therein. Further, the contact lugs or 100 fingers of each terminal plate are normally 105 engaged with the annular slots in the base. The base 105 has a central conductor opening 11 and a knot receiving recess 12 adjacent thereto. The base is provided with a lower end disk 5 to clamp an inturned rim 6 of the threaded shell 2 to the base. The opposite end of the base is centrally recessed to receive an annular contact 7, shown as cup-shaped, which in receives a cylindrical insulating block 8. All of the aforesaid parts are secured in assembled relation by the center contact screw. The contact 7 constitutes a center contact while the upper extremity of the screw shell 2 provides an outer annular contact 9 concentric with the former contact. The contact portion 9 of the screw shell is surrounded by an insulating collar 10 which in practice may be molded thereon or otherwise fixed thereto to serve as a gripping member for inserting the plug in a lamp socket and also for external insulation of the contact portion 9. Both contacts 7 and 9, as shown, are curved to provide concave gripping surfaces and both are closely walled in by the several insulating parts. Moreover, the insulating parts are extended slightly beyond the extremities of the contacts and the extremities of the contacts are set into their surrounding insulating walls whereby only their inner faces are accessible and then only after entrance between the extended insulating parts. Thus the cap receiving end of the plug part appears as a block of insulation with restricted concentric slots and presents a very neat appearance while it very effectually insures against accidental engagement with the contacts.

The cap 4 is provided with the usual central conductor opening 11 and with a knot receiving recess 12 adjacent thereto. Also, the cap is provided with the usual annular rim 13 and adjacent to said rim and at diametrically opposite points with terminal plates 15 and 16 having binding screws 17. The terminal plates, as best illustrated in Fig. 3, are arc shaped and arranged concentrically with the conductor opening while being spaced from one another. Terminal plate 15 is provided with perpendicularly and oppositely disposed contact lugs 18 and 19 and terminal plate 16 is provided with similar contact lugs 20 and 21, each of said lugs being arc shaped in cross section and longitudinally split to form a plurality of resilient fingers. The contact lugs are concentrically arranged with respect to the axis of the plug thereby giving free access to the knot recess and are so disposed as to register with the annular slots in the base for insertion therein. Further, the contact lugs or fingers of each terminal plate are normally engaged with the annular slots in the base. The base has a central conductor opening 11 and a knot receiving recess 12 adjacent thereto. The base is provided with a lower end disk 5 to clamp an inturned rim 6 of the threaded shell 2 to the base. The opposite end of the base is centrally recessed to receive an annular contact 7, shown as cup-shaped, which in receives a cylindrical insulating block 8. All of the aforesaid parts are secured in assembled relation by the center contact screw. The contact 7 constitutes a center contact while the upper extremity of the screw shell 2 provides an outer annular contact 9 concentric with the former contact. The contact portion 9 of the screw shell is surrounded by an insulating collar 10 which in practice may be molded thereon or otherwise fixed thereto to serve as a gripping member for inserting the plug in a lamp socket and also for external insulation of the contact portion 9. Both contacts 7 and 9, as shown, are curved to provide concave gripping surfaces and both are closely walled in by the several insulating parts. Moreover, the insulating parts are extended slightly beyond the extremities of the contacts and the extremities of the contacts are set into their surrounding insulating walls whereby only their inner faces are accessible and then only after entrance between the extended insulating parts. Thus the cap receiving end of the plug part appears as a block of insulation with restricted concentric slots and presents a very neat appearance while it very effectually insures against accidental engagement with the contacts.

The cap 4 is provided with the usual central conductor opening 11 and with a knot receiving recess 12 adjacent thereto. Also, the cap is provided with the usual annular rim 13 and adjacent to said rim and at diametrically opposite points with terminal plates 15 and 16 having binding screws 17. The terminal plates, as best illustrated in Fig. 3, are arc shaped and arranged concentrically with the conductor opening while being spaced from one another. Terminal plate 15 is provided with perpendicularly and oppositely disposed contact lugs 18 and 19 and terminal plate 16 is provided with similar contact lugs 20 and 21, each of said lugs being arc shaped in cross section and longitudinally split to form a plurality of resilient fingers. The contact lugs are concentrically arranged with respect to the axis of the plug thereby giving free access to the knot recess and are so disposed as to register with the annular slots in the base for insertion therein. Further, the contact lugs or fingers of each terminal plate are normally engaged with the annular slots in the base. The base has a central conductor opening 11 and a knot receiving recess 12 adjacent thereto. The base is provided with a lower end disk 5 to clamp an inturned rim 6 of the threaded shell 2 to the base. The opposite end of the base is centrally recessed to receive an annular contact 7, shown as cup-shaped, which in receives a cylindrical insulating block 8. All of the aforesaid parts are secured in assembled relation by the center contact screw. The contact 7 constitutes a center contact while the upper extremity of the screw shell 2 provides an outer annular contact 9 concentric with the former contact. The contact portion 9 of the screw shell is surrounded by an insulating collar 10 which in practice may be molded thereon or otherwise fixed thereto to serve as a gripping member for inserting the plug in a lamp socket and also for external insulation of the contact portion 9. Both contacts 7 and 9, as shown, are curved to provide concave gripping surfaces and both are closely walled in by the several insulating parts. Moreover, the insulating parts are extended slightly beyond the extremities of the contacts and the extremities of the contacts are set into their surrounding insulating walls whereby only their inner faces are accessible and then only after entrance between the extended insulating parts. Thus the cap receiving end of the plug part appears as a block of insulation with restricted concentric slots and presents a very neat appearance while it very effectually insures against accidental engagement with the contacts.

The cap 4 is provided with the usual central conductor opening 11 and with a knot receiving recess 12 adjacent thereto. Also, the cap is provided with the usual annular rim 13 and adjacent to said rim and at diametrically opposite points with terminal plates 15 and 16 having binding screws 17. The terminal plates, as best illustrated in Fig. 3, are arc shaped and arranged concentrically with the conductor opening while being spaced from one another. Terminal plate 15 is provided with perpendicularly and oppositely disposed contact lugs 18 and 19 and terminal plate 16 is provided with similar contact lugs 20 and 21, each of said lugs being arc shaped in cross section and longitudinally split to form a plurality of resilient fingers. The contact lugs are concentrically arranged with respect to the axis of the plug thereby giving free access to the knot recess and are so disposed as to register with the annular slots in the base for insertion therein. Further, the contact lugs or fingers of each terminal plate are normally engaged with the annular slots in the base. The base has a central conductor opening 11 and a knot receiving recess 12 adjacent thereto. The base is provided with a lower end disk 5 to clamp an inturned rim 6 of the threaded shell 2 to the base. The opposite end of the base is centrally recessed to receive an annular contact 7, shown as cup-shaped, which in receives a cylindrical insulating block 8. All of the aforesaid parts are secured in assembled relation by the center contact screw. The contact 7 constitutes a center contact while the upper extremity of the screw shell 2 provides an outer annular contact 9 concentric with the former contact. The contact portion 9 of the screw shell is surrounded by an insulating collar 10 which in practice may be molded thereon or otherwise fixed thereto to serve as a gripping member for inserting the plug in a lamp socket and also for external insulation of the contact portion 9. Both contacts 7 and 9, as shown, are curved to provide concave gripping surfaces and both are closely walled in by the several insulating parts. Moreover, the insulating parts are extended slightly beyond the extremities of the contacts and the extremities of the contacts are set into their surrounding insulating walls whereby only their inner faces are accessible and then only after entrance between the extended insulating parts. Thus the cap receiving end of the plug part appears as a block of insulation with restricted concentric slots and presents a very neat appearance while it very effectually insures against accidental engagement with the contacts.

spread so as to be slightly contracted when forced into the slots in the base and are provided with bulged extremities to spread after insertion into the slots for engagement 5 with the concave contacts of the base.

It will thus be apparent that the cap may be readily wired and knotted, and then plugged into the base by a straight push as with the ordinary separable plug but that 10 engagement of the coöperating contacts will not be effected until after an appreciable insertion of the cap contacts. Also, it will be apparent that due to the annular formation and concentric arrangement of the base contacts and the similar arrangement of the cap contacts, the cap after being plugged into the base may be freely rotated with respect thereto while maintaining firm electrical engagement therewith. Still further, it will 15 be apparent that with the arrangement of contacts shown said contacts will interlock contiguous to the line of division between the cap and the base and that the contacts of the cap will yield in all directions radially 20 of the axis of the plug whereby the cap may be readily detached either by straight pull or by leverage at any angle circumferentially of the plug. On the other hand, the contacts while readily separable are so constructed as to provide a relatively large contact area and by virtue of the resiliency and 25 opposed relation of the cap contacts to firmly engage throughout such contact area.

What I claim as new and desire to secure 30 by Letters Patent is:

1. A separable attachment plug comprising a plug part and a cap, said parts being provided with coöperating contacts providing a releasable connection therebetween and 40 certain of said contacts being annular and concentrically arranged to render said connection of a swivel type, said plug part having its contacts terminating in substantially the same transverse plane and having its cap 45 receiving end closed except for restricted openings to receive the cap contacts.

2. A separable attachment plug comprising a plug part and a cap, said parts having coöperating contacts providing a swivel and 50 releasable connection therebetween the contacts of said cap projecting substantially equal distances therefrom and said plug part having its cap receiving end closed except for restricted openings to receive the cap 55 contacts and also having its contacts adjacent to the surface of its cap receiving end.

3. A separable attachment plug comprising a plug part and a cap, said parts having coöperating contacts providing a swivel and 60 releasable connection therebetween, said plug part having its cap receiving end closed except for restricted openings to receive the cap contacts and having its contacts arranged in close proximity to the surface of 65 its cap receiving end and the contacts of said

cap being of substantially uniform length and resilient for permitting separation of said cap from said plug part either by leverage or by straight pull.

4. A separable attachment plug including 70 a plug part provided with concentric annular contacts and a cap therefor having a plurality of sets of normally spread contact lugs to be plugged within each of said annular contacts. 75

5. A separable attachment plug including a plug part provided with concentric annular contacts and continuous insulating walls exteriorly and interiorly of said contacts and a cap for said plug part provided with contacts to plug into engagement with said annular contacts through the slots provided by 80 said insulating walls.

6. A separable attachment plug comprising 85 a plug part, a one-piece centrally recessed cap therefor and plugging contacts for said parts providing a swivel connection therebetween, said cap having its contacts fixed thereto and arranged in non-obstructive relation with respect to the central opening 90 of said cap and said cap contacts having binding posts adjacent to said cap opening.

7. A separable attachment plug comprising 95 a plug part having contacts at varying distances from its central axis and a centrally recessed one-piece cap having coöperating plugging contacts fixed thereto arranged in a non-obstructive relation with respect to the central opening of said cap and provided with readily accessible binding posts adjacent to said opening. 100

8. A one-piece cap for separable attachment plugs provided with a central conductor opening and knot recess and further provided with contact plug fixed thereto 105 and projecting therefrom, said contacts having their projecting portions arranged at different distances from the central axis of said cap and having freely accessible binding posts adjacent to the central opening 110 of said cap.

9. A one-piece cap for separable attachment plugs provided with a central conductor opening and knot recess and further provided with diametrically opposed terminal plates respectively having contact extensions projecting therefrom, said terminal plates being adjacent to said conductor opening and said contact extensions being arranged at different distances from the 115 central axis of said cap and in a non-obstructive relation with respect to said knot recess and said terminal plates. 120

10. A plug part for separable attachment 125 plugs provided with an insulating end having concentric annular slots therein of restricted width and inclosed concentric annular contacts accessible only through said annular slots.

11. A plug part for separable attach- 130

- ment plugs provided with concentric annular contacts and insulating inclosing parts for said contacts having concentric annular slots therebetween to give access 5 to said contacts but said slots being relatively narrow.
12. A plug part for separable attachment plugs provided with concentric annular contacts and cylindrical insulating 10 walls within and without each contact to restrict the accessibility thereof, said walls projecting beyond the extremities of said contact.
13. A plug part for separable attachment plugs provided with concentric annular contacts and cylindrical insulating walls within and without each contact to restrict the accessibility thereof, said walls projecting beyond the extremities of said 20 contact and each of said contacts having a portion offset from the slot between its respective insulating walls.
14. A plug part for separable attachment plugs provided with a screw shell, a 25 center contact at its plugging end and at its opposite end with contacts for a cap part, one of said latter contacts comprising the end of said shell and the other being electrically connected with said center contact and insulating walls within and without each of said latter contacts.
15. A plug part for separable attachment plugs including a base provided at
- opposite ends with electrically connected contacts and with an external threaded shell serving as a side contact for the plugging end of said part and also as a second contact for the cap receiving end of said part and an insulating plug clamped within both contacts at the cap receiving end of 40 said plug part.
16. A plug part for separable attachment plugs including a base, a center contact for the plugging end thereof, an electrically connected annular contact provided at the cap end of said base, a threaded shell inclosing said base and providing a second annular contact for the cap end of said base and an insulating plug secured within said first mentioned annular contact. 45
17. A plug part for separable attachment plugs provided with a base recessed at one end, a cup-shaped contact arranged within said recess, an insulating block within said cup-shaped contact, a center 50 contact rod for the opposite end of said base providing means for securing all of said parts together, a threaded shell surrounding said base and forming a second annular end contact concentric with said cup-shaped contact and an insulating collar fixed to said end of said shell.

In witness whereof, I have hereunto subscribed my name.

CHARLES J. KLEIN.
